US00D996365S

(12) **United States Design Patent** (10) **Patent No.:** **US D996,365 S**
(45) **Date of Patent:** **** Aug. 22, 2023**

(54) **CONTAINER**

(71) Applicant: **Andrew G. C. Frazier**, Sunnyvale, CA (US)

(72) Inventor: **Andrew G. C. Frazier**, Sunnyvale, CA (US)

(**) Term: **15 Years**

(21) Appl. No.: **29/806,894**

(22) Filed: **Sep. 7, 2021**

(51) **LOC (14) Cl.** **13-02**

(52) **U.S. Cl.**

USPC **D13/119**

(58) **Field of Classification Search**

USPC D3/201, 211–219, 220, 222, 225, 226, D3/228, 230, 242, 243, 251, 252, 262, D3/265, 269, 273, 294, 328; D9/703, D9/705, 707, 711; D13/103, 107–109, D13/118, 119, 184, 199; 429/96–100, 429/164–170, 178

(57) **CLAIM**

The ornamental design for a container, as shown and described.

DESCRIPTION

FIG. 1 is a front perspective view of a container showing my new design;

FIG. 2 is a front plan view of the container of FIG. 1;

FIG. 3 is a rear plan view of the container of FIG. 1;

FIG. 4 is a right side view of the container of FIG. 1;

FIG. 5 is a left side view of the container of FIG. 1;

FIG. 6 is a top plan view of the container of FIG. 1;

FIG. 7 is a bottom plan view of the container of FIG. 1; and,

FIG. 8 is a rear perspective view of the container of FIG. 1. The broken lines depict portions of the container that form no part of the claimed design.

1 Claim, 6 Drawing Sheets
